RAILWAY SIGNALING

George R. Pflasterer, Swissvale, Pa., assignor to
The Union Switch & Signal Company, Swiss-
vale, Pa., a corporation of Pennsylvania

Application March 12, 1936, Serial No. 68,497

15 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding aspect 10 of the wayside signals whereby there is produced a three block, four indication system of signaling.

The apparatus provided by this invention is an improvement on the systems shown in the application of Howard A. Thompson, Serial No. 15 692,155, filed October 4, 1933, for Railway traffic controlling apparatus, and in the application of Henry S. Young, Serial No. 66,002, filed February 27, 1936, for Railway signaling.

20 I will describe several forms of apparatus each embodying my invention, and will then point out the novel features thereof in claims.

In the accompanying drawings, Figs. 1A and 1B are diagrammatic views which, when placed end to end in the order named, illustrate one form of 25 apparatus embodying my invention. Figs. 2A and 2B are diagrammatic views which, when placed end to end in the order named, illustrate another form of apparatus embodying my invention. Figs. 3A and 3B are diagrammatic views 30 which, when placed end to end in the order named, illustrate still another form of apparatus embodying my invention. Fig. 4 is a diagrammatic view illustrating in detail a portion of the apparatus illustrated in the foregoing figures. Figs. 5A and 5B are diagrammatic views which, 35 when placed end to end in the order named, illustrate still a different form of apparatus embodying my invention.

Similar reference characters refer to similar 40 parts in each of the several views.

Referring first to Figs. 1A and 1B, the reference characters 8 and 9 designate the rails of a stretch of railway track along which traffic normally moves in the direction indicated by the arrows. 45 These rails are divided by insulated joints 14 into a plurality of track sections or blocks W—X, X—Y, and Y—Z.

Each track section is divided by insulated joints 14 into at least two subsections 1T, 2T, 3T, 4T, 50 etc. Each subsection is provided with a track circuit which includes a track battery 15 connected across the rails at one end of the subsection and a track relay connected across the other end of the subsection. The track relays 55 are designated by the reference character TR

with a prefix the same as the numerical prefix in the reference character for the associated subsection.

To govern the passage of trains through the stretch of railway, a wayside signal, designated by a suitable distinguishing reference character, is located at the entrance to each track section. Each of these signals comprises an upper unit U and a lower unit L. These units may take any one of several forms of signal mechanism such as searchlight, semaphore, color light or position light. As here shown, each upper unit is a color light signal comprising a green lamp G, a yellow lamp Y, and a red lamp R; and each lower unit is a color light signal comprising a green lamp G 15 and a red lamp R.

Each section is provided with a polarized direct current signal control relay designated by the reference character H with a prefix the same as the reference character of the associated signal 20 and with an alternating current signal control relay designated by the reference character J with a prefix the same as the reference character of the associated signal.

Each section is provided with a line circuit including a pair of line wires extending to the signal next in advance and each of which includes a front contact of each of the associated track relays.

Each relay H is connected directly to the associated line wires and each relay J is also connected to the associated line wires through a condenser designated by the reference character D with a prefix the same as the reference character of the associated signal.

The condensers D prevent the flow of direct current in the alternating current relays J and the high impedance of the direct current relays H prevents the flow of alternating current in these relays.

Each section is provided with a suitable source of direct current, the terminals of which are designated by the reference characters B and C.

Each section is also provided with a device for 45 converting the direct current into alternating current and designated by the reference character A with a prefix the same as the reference character of the associated signal. As here shown, the devices A are the well known tuned reed alternators.

Associated with each alternator A is a transformer N, the primary winding of which is connected to the associated alternator and the secondary winding of which is at times effective to 55

supply alternating current to the line circuit for the section next in rear.

As will be explained more in detail hereinafter, the relays H and J control the line circuit for the section next in rear in such manner that this line circuit is supplied with direct current of one polarity or with direct current of the other polarity or with alternating current.

- Each of the color light signals is controlled by 10 the associated relays H and J in the following manner: When both relays are deenergized (see signal 13) the red lamp R of the upper unit U of that signal is lighted by a circuit which passes from terminal B through back point of contact 16 of relay 13H, back point of contact 17 of relay 13J, and lamp R to terminal C; and the red lamp R of the lower unit L of that signal is lighted by a circuit which passes from terminal B through back point of contact 18 of relay 13H and lamp R to terminal C. Signal 13, therefore, displays a red light above a red light to indicate "stop". When relay H is deenergized and relay J is energized (see signal 12) the yellow lamp Y of the upper unit U of that signal is lighted by a circuit which passes from terminal B through back point of contact 19 of relay 12H, front point of contact 20 of relay 12J, and lamp Y to terminal C; and the red lamp R of the lower unit L of that signal is lighted by a circuit which passes from terminal B through back point of contact 21 of relay 12H and lamp R to terminal C. Signal 12, therefore, displays a yellow light above a red light to indicate "prepare to stop at next signal". When relay H is energized in the reverse direction (see signal 11) the yellow lamp Y of the upper unit U of that signal is lighted by a circuit which passes from terminal B through front point of contact 22 of relay 11H, reverse polar contact 23-24 of relay 11H, and lamp Y to terminal C; and the green lamp G of the lower unit L of that signal is lighted by a circuit which passes from terminal B through front point of contact 25 of relay 11H, reverse polar contact 26-27 of relay 11H, and lamp G to terminal C. Signal 11, therefore, displays a yellow light above a green light to indicate "approach next signal at medium speed". When relay H is energized in the normal direction (see signal 10) the green lamp G of the upper unit U of that signal is lighted by a circuit which passes from terminal B through front point of contact 28 of relay 10H, normal polar contact 23-29 of relay 10H, and lamp G to terminal C; and the red lamp R of the lower unit L of that signal is lighted by a circuit which passes from terminal B through front point of contact 30 of relay 10H, normal polar contact 26-31 of relay 10H, and lamp R to terminal C. Signal 10, therefore, displays a green light above a red light to indicate "proceed at normal speed".
- As shown in the drawings, the section immediately to the right of point Z is occupied by a train K, so that both relays 13H and 13J are deenergized. When relays 13H and 13J are deenergized, alternator 13A is supplied with direct current energy over a circuit which passes from terminal B through back contact 32 of relay 13H, back contact 33 of relay 13J, wire 34, and alternator 13A to terminal C, so that alternator 13A supplies alternating current to the primary winding 35 of transformer 13N. When alternating current is supplied to primary winding 35 and both relays 13H and 13J are deenergized, alternating current relay 12J is energized by alternating current over a circuit which passes from one terminal of secondary winding 36 of transformer

13N through wire 37, back point of contact 38 of relay 13J, back point of contact 39 of relay 13H, front contact 40 of track relay 6TR, front contact 41 of track relay 5TR, relay 12J, condenser 12D, front contact 42 of relay 5TR, front contact 43 of relay 6TR, back point of contact 44 of relay 13H, back point of contact 45 of relay 13J and wire 46 to the other terminal of primary winding 36. When relay 12J is energized and relay 12H is de-energized, relay 11H is energized by direct current in the reverse direction over a circuit which passes from terminal B, at signal 12, through front point of contact 47 of relay 12J, back point of contact 48 of relay 12H, front contact 49 of relay 4TR, front contact 50 of relay 3TR, relay 15 11H, front contact 51 of relay 3TR, front contact 52 of relay 4TR, back point of contact 53 of relay 12H, and front point of contact 54 of relay 12J to terminal C. When relay 11H is energized, relay 10H is energized by direct current in the normal direction over a circuit which passes from terminal B through front point of contact 55 of relay 11H, front contact 56 of relay 2TR, front contact 57 of relay 1TR, relay 10H, front contact 58 of relay 1TR, front contact 59 of relay 2TR, and front point of contact 60 of relay 11H to terminal C. It will be readily apparent that when relay 10H is energized the line circuit for the section next in rear of section W-X is supplier over front contacts of relay 13H, with direct current energy in the normal direction so that the signal (not shown) for such rear section is displaying its normal proceed indication.

To sum up thus far, each signal is controlled by a direct current polarized signal control relay and by an alternating current signal control relay both receiving energy over a line circuit which is controlled by the track relays of the section with which the signal is associated and by the signal control relays of the signal next in advance. When both signal control relays are deenergized the associated signal indicates "stop" and the line circuit to the rear is supplied with alternating current energy only. When the alternating current relay alone is energized the associated signal indicates "prepare to stop at next signal" and the line circuit to the rear is supplied only with direct current of reverse polarity. When the direct current relay is energized in the reverse direction the associated signal indicates "approach next signal at medium speed" and the line circuit to the rear is supplied only with direct current of normal polarity. When the direct current relay is energized in the normal direction the associated signal indicates "proceed at normal speed" and the line circuit to the rear is supplied only with direct current of normal polarity so that the signal controlled by such rear line circuit will also display the normal proceed indication.

It will be noted the alternator A at each signal is caused to operate only when the associated section is occupied by a train. Since under ordinary conditions the stretch of railway will be unoccupied the greater part of the time, the energy consumed by the alternators will be relatively small. This feature, therefore, provides a simple and economical method for providing alternating current at each signal which method is particularly desirable when the direct current energy is supplied by primary batteries which must be renewed from time to time.

It will also be noted the polarized signal control relays H are of the retained neutral type, that is, the neutral armatures of these relays do

not release during changes of polarity. This characteristic prevents momentary flashing of a red lamp of the associated signal and tumble-down of the signal control relays to the rear. For example, when the train K vacates the section to the right of location Z so that the line circuit for the section X—Y is supplied with direct current energy in the normal direction to cause signal 11 to display a green light above a red light instead of a yellow light above a green light, the neutral contacts of relay 11H will remain in their energized position, as shown in Fig. 1A, during the period of change in polarity. Since the back points of the neutral contacts of relay 11H do not become closed, the circuit for the red lamp R of the upper unit U of signal 11 cannot become closed to cause a momentary flash of that lamp, and since the front points of the neutral contacts of relay 11H do not become opened, the line circuit for the section W—X will remain closed so that the energization of relay 10H will not be disturbed. Consequently, momentary flashing of the red lamps and successive tumble-down of the signal control relays to the rear are avoided.

Each of the retained neutral polarized signal control relays H functions, during pole-changing periods, in a manner similar to that described for relay 11H.

Referring next to Figs. 2A and 2B, the system illustrated herein functions in many respects similar to that described for the system illustrated in Figs. 1A and 1B. The principal difference is in the type of wayside signal utilized. As here shown, each upper unit UA is a signal mechanism of the searchlight type which may be substantially as described and claimed in United States Letters Patent No. 1,864,224, issued June 21, 1932, to W. B. Wells for Light signal; and each lower unit LA is a lamp Y capable of displaying a yellow light. For the purpose of this application it is deemed sufficient to but briefly describe these searchlight signals. Upper unit UA of signal 10, for example, includes a pivotally mounted rotor 62 controlled by a permanent magnet (not shown) and by an operating winding 63. Energization of operating winding 63 by current of one polarity causes rotor 62 to be rotated in one direction, moving the signal to the clear indication position; energization of operating winding 63 by current of the other polarity causes rotor 62 to be rotated in the opposite direction to move the signal to the caution indication position; while deenergization of operating winding 63 permits rotor 62 to be released by gravity to a center position, which is the stop indication position. Associated with rotor 62 is a signal lamp 10E. As pointed out in detail in the aforementioned patent, when rotor 62 is rotated to the clear position, a green colored filter G is moved in front of lamp 10E, so that a green signal light is displayed when lamp 10E is lighted. When rotor 62 is rotated to the caution indication position, a yellow colored filter Y is moved in front of lamp 10E so that a yellow signal light is displayed when lamp 10E is lighted. In like manner, the positioning of rotor 62 in the center position moves a red colored filter R in front of lamp 10E so that a red signal light is displayed when lamp 10E is lighted.

Each of the other searchlight signals functions in a manner similar to that described for signal 10.

Each section is provided with an approach lighting relay designated by the reference character ER with a prefix the same as the reference

character of the associated signal and connected in series with the line circuit for the section next in rear only when that line circuit is supplied with direct current energy.

Each lamp E is controlled by a back contact of the associated relay ER so that whenever the approach lighting relay is deenergized the associated lamp is lighted. For example, the lamp 13E is controlled over an easily traced circuit which includes back contact 61 of relay 13ER. Since each of the other lamps E is controlled in a similar manner by the associated relay ER, it will be obvious that each lamp E will be lighted whenever the associated relay ER is deenergized; that is, whenever the line circuit controlling such relay is opened or is supplied with alternating current energy. In other words, the relays ER will become deenergized whenever the associated section or the section next in rear becomes occupied by a train.

Each section is provided with the usual direct current polarized relay signal control relay H of the retained neutral type and with a direct current neutral signal control relay V.

Both signal control relays receive energy over the usual line circuit extending to the signal next in advance and controlled by the track relays of the associated section and by the two signal control relays of such advance signal. The polarized relay H is connected directly to the associated line circuit and the neutral relay V is connected to the associated line circuit through a rectifier, a transformer and a resistor designated by the reference characters Q, M, and F, respectively, each with a prefix the same as the reference character of the associated signal.

The resistors F will prevent the excessive flow of direct current in the primary windings of the transformers M, and the transformers M will prevent the flow of any direct current in the relays V. The high impedance of the direct current relays H will prevent the flow of alternating current in these relays.

Associated with each section is the usual alternator A and transformer N both of which are controlled by the associated relays H and V in a manner similar to that described for the apparatus shown in Figs. 1A and 1B. That is, whenever a section is occupied by a train, the alternator A is connected to the source of direct current and the secondary winding 36 of the transformer N is connected to the line circuit for the section next in rear to supply that line circuit with alternating current energy.

The relays H and V control the associated signals in the following manner: When both relays H and V are deenergized (see signal 13) both operating windings 63 of the upper unit UA and lamp Y of the lower unit LA of that signal are deenergized so that, with lamp 13E lighted, the signal displays a single red light to indicate "stop". When the neutral relay N is energized and the polarized relay is deenergized (see signal 12) operating winding 63 of the upper unit UA of that signal is energized in the reverse direction by a circuit which passes from terminal B through front contact 64 of relay 12V, back point of contact 65 of relay 12H, operating winding 63, back point of contact 66 of relay 12H, and front contact 67 of relay 12V to terminal C so that, when lamp 12E is lighted, signal 12 is in condition to display a single yellow light to indicate "approach next signal prepared to stop". When relay H is energized in the reverse direction (see signal 11) operating wind-

ing 63 of upper unit UA of that signal is energized in the reverse direction by a circuit which passes from terminal B through reverse polar contact 68—69 of relay 11H, front point of contact 70 of relay 11H, winding 63, front point of contact 71 of relay 11H, and reverse polar contact 72—73 of relay 11H to terminal C; and the lower unit LA of that signal is energized by a circuit which passes from terminal B through reverse polar contact 74—75 of relay 11H, front contact 76 of relay 11H and lamp Y to terminal C. Signal 11, therefore, when lamp 11E is lighted is in condition to display a yellow lamp above a yellow lamp to indicate "approach next signal at medium speed". When relay H is energized in the normal direction (see signal 10) operating winding 63 of upper unit UA of that signal is energized by a circuit which passes from terminal B through normal polar contact 77—72 of relay 10H, front point of contact 78 of relay 10H, operating winding 63, front point of contact 79 of relay 10H, and normal polar contact 69—80 of relay 10H to terminal C, so that, when lamp 10E is energized, signal 10 is in condition to display a single green light to indicate "proceed at normal speed".

Since the relays H and V control the line circuits for the section next in rear in exactly the same manner as described for the relays H and J, shown in Figs. 1A and 1B, it is thought that a detailed explanation is not required for the apparatus shown in Figs. 2A and 2B. It will be considered sufficient to state that when both relays H and V are deenergized, the line circuit to the rear will be supplied with alternating current energy only, when relay V only is energized, the line circuit to the rear will be supplied in the reverse direction with direct current only, and when the relay H is energized in either direction, its line circuit to the rear will be supplied in the normal direction with direct current only.

Summing up for the system illustrated in Figs. 2A and 2B, it will be seen that when a section is occupied by a train, the signal for that section will display a stop indication comprising a single red light; and the signals for the first, second, and third sections in rear of such occupied section will display, respectively, an approach indication comprising a single yellow light, an approach medium indication comprising two yellow lights and a proceed indication comprising a single green light provided that another train is occupying the section immediately in rear of such signals so that the associated approach lighting relay EP is deenergized.

It will be readily apparent that the retained neutral feature of the relays H will prevent successive tumble-down of the signal control relays to the rear as previously explained for the relays H shown in Figs. 1A and 1B.

Referring now to Figs. 3A and 3B, the system illustrated herein is similar in many respects to the systems illustrated in the previous figures. The principal difference lies in the fact that alternating current is supplied to the line circuit for the control of the second proceed indication in rear of an occupied section whereas in the systems illustrated in Fig. 1A and 1B and in Figs. 2A and 2B, alternating current is supplied to the line circuit for the control of the first proceed indication in rear of an occupied section.

Each section is provided with a signal having an upper unit U comprising a red, a yellow, and a green lamp and a lower unit L comprising a red and a green lamp.

Each section is provided with a polarized direct current signal control relay HA and with the usual neutral direct current signal control relay V.

Each polarized relay HA is connected directly to the associated line circuit and each neutral relay V is connected to such associated line circuit through a rectifier Q, a transformer M, and a condenser D.

The high impedance of the direct current relay HA will prevent its flow of alternating current in these relays and with the condensers D and transformers M will prevent the flow of direct current in the relays V.

Each section is provided also with the usual alternator A for supplying alternating current to the line circuit for the section next in rear.

Associated with each section is a pole-changing relay designated by the reference character HP with a prefix the same as the reference character of the associated signal. The relays HP have a slow releasing characteristic and are utilized to control jointly with the associated relays HA and V, the line circuit for the section next in rear.

25

The relays HA and V control the associated signals in the following manner: When both relays HA and V are deenergized (see signal 13) the red lamp R of the upper unit U of that signal is lighted by a circuit which passes from terminal B through back point of contact 81 of relay 13HA, back point of contact 82 of relay 13V and lamp R to terminal C; and the red lamp R of the lower unit L of that signal is lighted by a circuit which passes from terminal B through back point of contact 83 of relay 13V and lamp R to terminal C. Signal 13, therefore, is displaying a red light above a red light to indicate "stop". When relay HA is energized in the reverse direction and relay V is deenergized (see signal 12) the yellow lamp Y of the upper unit U of that signal is lighted by a circuit which passes from terminal B through front point of contact 84 of relay 12HA, reverse polar contact 85—86 of relay 12HA and lamp Y to terminal C; and the red lamp R of the lower unit L of that signal is lighted by a circuit which passes from terminal B through back point of contact 87 of relay 12V and lamp R to terminal C. Signal 12, therefore, is displaying a yellow light above a red light to indicate "proceed to stop at next signal". When relay HA is deenergized and relay V is energized (see signal 11) the yellow lamp Y of the upper unit U of that signal is lighted by a circuit which passes from terminal B through back point of contact 88 of relay 11HA, front point of contact 89 of relay 11V, and lamp Y to terminal C; and the green lamp G of the lower unit L of that signal is lighted by a circuit which passes from terminal B through front point of contact 90 of relay 11V, and lamp G to terminal C. Signal 11, therefore, is displaying a yellow light above a green light to indicate "approach next signal at medium speed." When relay V is deenergized and relay HA is energized in the normal direction (see signal 10) the green lamp G of the upper unit U of that signal is lighted by a circuit which passes from terminal B through front point of contact 91 of relay 10HA, normal polar contact 85—92 of relay 10HA, and lamp G to terminal C; and the red lamp R of the lower unit L of that signal is lighted by a circuit which passes from terminal B through back point of contact 93 of relay 10V, and lamp R to terminal C. Signal 10, therefore, is displaying a green light above a red light.

a red light to indicate "proceed at normal speed".

As shown in the drawings, the section immediately to the right of location Z is occupied by the train K so that both relays 13HA and 13V are deenergized. When both relays 13HA and 13V are deenergized, the relay 12HA is energized by direct current in the reverse direction over a circuit which passes from terminal B, at signal 13, through back point of contact 94 of relay 13HA, back contact 95 of relay 13V, wire 46, secondary winding 36 of transformer 13N, wire 37, back point of contact 97 of relay 13HP, front contact 98 of relay 6TR, front contact 99 of relay 5TR, relay 12HA, front contact 100 of relay 5TR, front contact 101 of relay 6TR, and back point of contact 102 of relay 13HP to terminal C. When relay 12HA is energized in the reverse direction and relay 12V is deenergized, alternator 12A is energized by direct current over a circuit which passes from terminal B through back contact 103 of relay 12V, front contact 104 of relay 12HA, reverse polar contact 105—106 of relay 12HA, wire 34, and alternator 12A to terminal C; and relay 11HA is energized by alternating current over a circuit which passes from one terminal of secondary 36 of transformer 12N through wire 37, back point of contact 107 of relay 12HP, front contact 108 of relay 4TR, front contact 109 of relay 3TR, condenser 11D, transformer 11M, rectifier 11Q, relay 11V, front contact 110 of relay 3TR, front contact 111 of relay 4TR, back point of contact 112 of relay 12HP, front point of contact 113 of relay 12HA, back contact 114 of relay 12V, and wire 46 to the other terminal of secondary winding 36 of transformer 12N. When relay 11V is energized and relay 11HA is deenergized, relay 11HP is energized by a circuit which passes from terminal B through front point of contact 115 of relay 11V, back point of contact 116 of relay 11HA and relay 11HP to terminal C; and relay 10HA is energized by direct current in the normal direction over a circuit which passes from terminal B, at signal 11, through front point of contact 117 of relay 11HP, front contact 118 of relay 2TR, front contact 119 of relay 1TR, relay 10HA, front contact 120 of relay 1TR, front contact 121 of relay 2TR, and front point of contact 122 of relay 11HP to terminal C. When relay 10HA is energized in the normal direction and relay 10V is deenergized, relay 10HP is energized over a circuit which passes from terminal B through back point of contact 123, normal polar contact 124—125 of relay 10HA, front point of contact 126 of relay 10HA, and relay 10HP to terminal C; and the line circuit for the section next in rear of section W—X is supplied with direct current energy in the normal direction over front points of contact of relay 10HP so that the signal (not shown) controlled by that line circuit is also displaying its normal proceed indication.

In the signaling systems illustrated in Figs. 3A and 3B, therefore, the two signal control relays function as follows: When both relays are deenergized, the associated signal indicates "stop" and the line circuit to the rear is supplied only with direct current energy in the reverse direction. When the polarized relay is energized in the reverse direction and the neutral relay is deenergized, the associated signal indicates "prepare to stop at next signal" and the line circuit to the rear is supplied only with alternating current energy. When the neutral

relay is energized and the polarized relay is deenergized, the associated signal indicates "approach next signal at medium speed" and the line circuit to the rear is supplied only with direct current in the normal direction. When the polarized relay is energized in the normal direction and the neutral relay is deenergized, the associated signal indicates "proceed at normal speed" and the line circuit to the rear is supplied only with direct current energy in the normal direction so that the signal (not shown) controlled by that line circuit is also displaying the normal proceed indication.

It will be noted that the pole changing relays HP have a slow releasing characteristic. This feature prevents momentary opening of the line circuit to the rear so that successive tumble-down of the signal control relays to the rear is avoided. For example, when the train K passes out of the section to the right of signal 13 so that relay 11HA becomes energized in the normal direction and relay 11V becomes deenergized to cause signal 11 to display the normal indication, energization of relay 11HP is transferred from the circuit which includes front point of contact 115 of relay 11V and back point of contact 116 of relay 11HA to a circuit which includes back point of contact 115 of relay 11V, reverse polar contact 129—125 of relay 11HA, and front point of contact 116 of relay 11HA. Relay 11HP, however, does not open the front points of its contacts 117 and 122 during this transfer of control so that energization of the line circuit for section W—X and successive sections to the rear is not disturbed.

Referring now to Fig. 4, which illustrates the alternators A in detail, the reference character 130 designates an elastic member which is caused to vibrate between terminals 131 and 132 by a control winding 133. In the deenergized condition, member 130 does not connect with either terminal 131 or 132 but does connect with a terminal 134. When energy is supplied to the alternator A, winding 133 will attract member 130 causing it to connect with terminal 132 and to move away from terminal 134, causing winding 133 to become deenergized. Upon the deenergization of winding 133, the resilience of member 130 will cause it to move away from terminal 132 and to connect with terminal 131 as well as with terminal 134. The circuit for winding 133 being then again completed through terminal 134, winding 133 will again attract member 130 causing the cycle of operation just described to be repeated. Winding 133 will then be repeatedly energized and deenergized as long as energy is supplied to its control circuit.

When member 130 connects with terminal 132, current is supplied to the right-hand portion of the primary winding 35 of the transformer N; and when member 130 connects with terminal 131, current is supplied in the opposite direction to the left-hand portion of primary winding 35. Alternating current, therefore, will be induced in the secondary winding 36 of transformer N.

It will be readily apparent from the foregoing description how the alternators A will supply alternating current to the line circuit for the section next in rear when that line circuit is connected to wires 37 and 46 provided, of course, that wire 34 is connected to terminal B and that winding 133 is connected to terminal C.

Referring now to Figs. 5A and 5B, each section is provided with a signal which comprises an upper unit UA and a lower unit LB both of

which are similar in all respects to the searchlight signal mechanisms UA of the signals shown in Figs. 2A and 2B with the exception that the lower units LB are capable of displaying a green light or a red light but not a yellow light.

In addition to the usual source of direct current, the terminals of which are identified by the reference characters B and C, each section is provided also with a source of alternating current the terminals of which are designated by the reference characters BX and CX. This source of alternating current may be any convenient commercial source or may be generated locally at each signal by apparatus not shown.

15 Each upper searchlight mechanism is provided with a lamp UE and each lower searchlight mechanism is provided with a lamp LE.

Associated with each section for controlling the associated lamps UE and LE is an approach lighting relay designated by the reference character ER with a prefix the same as the reference character of the associated signal.

Each approach lighting relay ER is connected in series with the line circuit for the section next in rear and is provided with an asymmetric unit 135 connected across its operating winding and poled so as to force the direct current to flow through the operating winding but to permit each half-wave of the alternating current to by-pass the operating winding. Each relay ER, therefore, remains energized as long as the line circuit with which it is associated remains closed regardless of whether such line circuit is supplied with direct current or with alternating current.

35 The lamps UE and LE are controlled by a back contact of the associated relay ER so that these lamps become lighted only when such relay ER is deenergized. For example, the lamps 13UE and 13LE at signal 13 are both governed by back contact 144 of relay 13ER. Since relay 13ER will become deenergized so that its back contact 144 will be closed only when section Y-Z is occupied by a train, lamps 13UE and 13LE will be lighted only when section Y-Z is occupied.

40 Each of the lamps UE and LE for the remaining signals is controlled by the associated relay ER in a manner similar to that just described for signal 13.

Operably connected to each upper unit UA is a contact 136-137 which becomes closed only 50 when the signal is in the clear indication position, a contact 136-138 which becomes closed when the signal is in either the caution or stop indication position, a contact 139-140 which becomes closed only when the signal is in the caution indication position, and a contact 139-141 which becomes closed when the signal is in either the clear or stop indication position.

Operably connected to each lower unit LB is a contact 142-143 which becomes closed only when 60 the signal is in the clear indication position.

Each section is provided with a line circuit including a pair of line wires controlled by the associated track relays and extending to the signal for the section next in advance.

65 Each lower mechanism LB is connected to the associated line circuit through a rectifier, a transformer and a condenser designated by the reference characters Q, M, and D, respectively, each with a prefix the same as the reference characters of the associated signal. That is, each mechanism LB responds only when its line circuit is supplied with alternating current.

Associated with each section is a repeating relay designated by the reference character LP

75 with a prefix the same as the reference character of the associated signal. Each relay LP is controlled by the lower mechanism LB of the associated signal and receives its energy over the associated line circuit. That is, each LP relay is energized only when the associated lower mechanism is also energized. For example, the relay 10LP is controlled over clear contact 142-143 of lower mechanism LB of signal 10 so that when the mechanism is energized the relay 10LP also receives energy from the line circuit which supplies energy to the lower mechanism LB.

Each upper mechanism UA is connected to the associated line circuit through either front or 15 back contacts of the associated relay LP. When the relay LP is deenergized, that is, when the associated line circuit is not being supplied with alternating current energy, the upper mechanism is connected directly to the line circuit, 20 whereas when relay LP is energized, that is, when the associated line circuit is supplied with alternating current energy, the upper mechanism is connected to the line circuit through rectifier Q, transformer E, and condenser D.

25 In other words, the upper mechanism UA of each signal is responsive to direct current only but both mechanisms UA and LB are responsive to alternating current. As will be explained more in detail hereinafter, the relays LP are effective 30 also for connecting other relays to the associated line circuit when the relays LP are energized.

Associated with each section is a pole changing relay designated by the reference character PC with a prefix the same as the reference character of the associated signal. Each relay PC is governed by the upper signal mechanism UA of the associated signal in such a manner that each relay PC is energized only when the upper mechanism UA of the associated signal is in 40 either its clear or caution indication position. For example, relay 10PC may be energized by a circuit which includes clear contact 136-137 as well as clear and stop contact 139-141 of the upper mechanism UA of signal 10, or may be 45 energized by another circuit which includes caution contact 139-140 as well as caution and stop contact 136-138 of such upper mechanism UA. Each relay PC is effective for governing the polarity of the direct current energy supplied 50 to the line circuit for the section next in rear.

Associated with each section is another repeating relay designated by the reference character UP with a prefix the same as the reference character of the associated signal. Each 55 relay UP is governed by the upper signal mechanism UA of the associated signals. For example, the relay 10UP is governed by clear contact 136-137 of upper mechanism UA of signal 10 so that relay 10UP is energized only when such 60 mechanism is in its clear indication position.

Also associated with each section is an alternating current power transfer relay designated by the reference character PO with a prefix the same as the reference character of the associated 65 signal. Each relay PO is governed by the associated source of alternating current and by the associated relay UP. For example, the relay 10PO is governed by front contact 145 of relay 10UP so that relay 10PO will be energized only 70 when relay 10UP is energized provided that the alternating current is present at signal 10.

Each relay PO is effective to connect the line circuit for the section next in rear with the associated source of alternating current or with the 75

associated source of direct current depending upon whether such relay PO is energized or de-energized, respectively.

The operation of the signaling system illustrated in Figs. 5A and 5B will probably be best understood by tracing the circuits and explaining the operation simultaneously. As shown in the drawings, a train K occupies the section immediately to the right of signal 13 so that both upper and lower mechanisms of that signal are deenergized. Signal 13, therefore, when lamps 13UE and 13LE are lighted will display a red light above a red light to indicate "stop". When signal 13 is in this condition, relay 13PC is deenergized and relay 13UP is also deenergized so that relay 13PO likewise is deenergized.

Since both relays 13PC and 13PO are deenergized, operating winding 63 of upper mechanism UA of signal 12 is supplied with direct current energy in the reverse direction over a circuit which passes from terminal B, at signal 13, through back point of contact 146 of relay 13PO, approach lighting relay 13ER, back point of contact 141 of relay 13PC, front contact 148 of relay 6TR, front contact 149 of relay 5TR, back point of contact 150 of relay 12LP, operating winding 63 of signal 12, back point of contact 151 of relay 12LP, front contact 152 of relay 5TR, front contact 153 of relay 6TR, back point of contact 154 of relay 13PC, and back point of contact 155 of relay 13PO to terminal C. Signal 12, therefore, when lamps 12UE and 12LE are lighted, will display a yellow light above a red light to indicate "prepare to stop at next signal". When signal 12 is in this condition, relay 12PC is energized by a circuit which passes from terminal B through back point of contact 156 of relay 12LP, caution and stop contact 136-138 as well as caution contact 139-140 of signal 12, relay 12PC, and back point of contact 157 of relay 12LP.

When relay 12PC is energized and relay 12PO is deenergized, operating winding 63 of upper mechanism UA of signal 11 is supplied with direct current in the normal direction over a circuit which passes from terminal B through back point of contacts 158 of relay 12PO, relay 12ER, front point of contact 159 of relay 12PC, front contact 160 of relay 4TR, front contact 161 of relay 3TR, back point of contact 162 of relay 11LP, operating winding 63 of signal 11, back point of contact 163 of relay 11LP, front contact 164 of relay 3TR, front contact 165 of relay 4TR, front point of contact 166 of relay 12PC, and back point of contact 167 of relay 12PO to terminal C. Signal 11, therefore, when lamps 11UE and 11LE are lighted, will display a green light above a red light to indicate "approach next signal at medium speed". When signal 11 is in this condition, relay 11UP is energized by a circuit which passes from terminal B through back point of contact 168 of relay 11LP, clear contact 136-137 of signal 11, relay 11UP, and back point of contact 169 of relay 11LP to terminal C; relay 11PO is energized over front contact 170 of relay 11UP; and relay 11PC is energized over a circuit which passes from terminal B over the same path as just traced for relay 11UP up to and including clear contact 136-137 of signal 11, and thence through clear and stop contact 139-141 of signal 11, relay 11PC and back point of contact 169 of relay 11LP.

Since both relays 11PC and 11PO are energized, the primary winding 171 of transformer 10M will

be supplied with alternating current energy over a circuit which passes from terminal BX, at signal 12, through front point of contact 172 of relay 11PO, relay 11ER, front point of contact 173 of relay 11PC, front contact 174 of relay 2TR, front contact 175 of relay 1TR, condenser 10D, primary winding 171 of transformer 10M, front contact 176 of relay 1TR, front contact 177 of relay 2TR, front point of contact 178 of relay 11PC and front point of contact 179 of relay 11PO to terminal CX.

When primary winding 171 of transformer 10D is energized, current is induced in the secondary winding 184 of this transformer so that alternating current is supplied to the alternating current input terminals of the rectifier 10Q. Consequently, operating winding 63 of the lower mechanism LB of the signal 10, which mechanism is connected to the direct current output terminal of the rectifier 10Q, is supplied with direct current of normal polarity so that this mechanism is caused to assume its clear indication position.

When the lower mechanism LB of signal 10 is in its clear indication position, relay 10LP is energized by a circuit which passes from one direct current output terminal of rectifier 10Q through clear contact 142-143 of signal 10, and relay LP to the other direct current output terminal of rectifier 10Q.

When relay 10LP is energized, the operating winding 63 of the upper mechanism UA of signal 10 is energized in the normal direction over a circuit which passes from one direct current output terminal of rectifier 10Q through front point of contact 180 of relay 10LP, operating winding 63, and front point of contact 181 of relay 10LP to the other output terminal of rectifier 10Q.

Signal 10, therefore, when lamps 10UE and 10LE are lighted, is in condition to display a green light above a green light to indicate "proceed at normal speed".

When signal 10 is in this condition, relay 10UP is energized by a circuit which passes from one output terminal of rectifier 10Q through front point of contact 182 of relay 10LP, clear contact 136-137 of signal 10, relay 10UP, and front point of contact 183 of relay 10LP to the other output terminal of rectifier 10Q; relay 10PC is energized by a circuit which passes from one output terminal of rectifier 10Q through front point of contact 182 of relay 10LP, clear contact 136-137 as well as clear and stop contact 139-141 of signal 10, relay 10PC, and front point of contact 183 of relay 10LP to the other output terminal of rectifier 10Q; and relay 10PO is energized by a circuit which passes from terminal BX through front contact 145 of relay 10UP, and relay 10PO to terminal CX.

Since both relays 10PC and 10PO are energized, it is readily apparent that the line circuit for the section next in rear is supplied with alternating current energy so that the signal (not shown) controlled by that line circuit is also in its normal proceed condition.

It will be noted that both the relays PC and UP have a slow release characteristic. The feature of relays UP prevents the momentary release of the associated relays PO when the control of the relays UP is being transferred from the back to the front points of the contacts of the associated relays LP, and this feature of the relays PC prevents the momentary release of the relays PC when the control for these relays is being transferred from the back.

to the front points of the contacts of the associated relays LP as well as when the control for these relays is being transferred from the caution contacts to the clear contacts of the associated signal. Since the relays PC and PO do not become released during such periods, the energization of the line circuit for the section next in rear is not disturbed and, consequently, successive tumble-down of the signal control circuits to the rear is avoided. For example, when the train K moves out of the section to the right of location Z so that the line circuit for signal 11 is supplied with alternating current energy to cause signal 11 to assume the 15 normal proceed condition, the control circuit for relay 11UP will be opened momentarily during the time the control is being transferred from the back points of contacts 168 and 169 of relay 11LP to the front points of these contacts. The 20 slow release characteristics of relay 11UP, however, will maintain its front contact 170 closed during this period so that relay 11PO will not become released. Or, for example, when the train K vacates the section to the right of location Z so that signal 12 is caused to assume the 25 condition proper for displaying a green light above a red light instead of a yellow light above a red light, the control circuit for relay 12PC will be opened momentarily during the time the 30 control for this relay is being transferred from the caution contact 139—140 to the clear contact 136—137 of signal 12. Relay 12PC, however, due to its slow release characteristic will maintain its contacts in the energized condition during 35 this period.

As hereinbefore pointed out, each section is provided with a source of direct current and with a source of alternating current. When a section is occupied by a train, the energy required 40 by the lamps for the associated signal as well as the energy required for the line circuit for the section next in rear will be supplied by the source of direct current at such signal. For example, the line circuit for section Y—Z is supplied with energy from the source of direct current at signal 13 and the lamps 13UE and 13LE would be also supplied with energy from this 45 source of direct current if relay 13ER should become deenergized by another train occupying section Y—Z. The circuit for lamps 13UE and 13LE may be traced from terminal B through back point of contact 146 of relay 13PO, back contact 144 of relay 13ER, lamps 13UE and 13LE in multiple, and back point of contact 155 of 50 relay 13PO to terminal C.

At signal 12, the energy required by relay 12PC and the energy required by the line circuit for section X—Y as well as the energy which may be required to light the lamps 12UE and 12LE 55 is all supplied by the source of direct current at that signal.

At signal 11, the energy required by relays 11PC and 11UP is supplied by the source of direct current at that signal but the energy required by the line circuit for the section W—X and the energy required by relay 11PO as well as the energy which may be required for the lamps 11UE and 11LE is supplied by the source of alternating current at that signal.

At signal 10, the energy required for the relays 10LP, 10PC, 10PO, and 10UP and the energy required for the line circuit for the section next in rear as well as the energy which may be required by the lamps 10UE and 10LE is supplied

entirely by the source of alternating current at that signal.

In the event of failure of the source of alternating current, my system will function as a two indication signaling system. For example, if the alternating current at signal 11 should become absent, the relay 11PO would become deenergized so that the back points of its contacts 172 and 179 would become closed to supply direct current energy in the normal direction 10 to the line circuit for the control of signal 10 with the result that signal 10 would assume the condition proper for displaying a green light above a red light instead of the normal proceed indication. 15

To sum up regarding the two sources of current, each signal is provided with an alternating current source of energy which supplies the entire load required by my system as long as the signals display their normal proceed indication, and each signal is supplied with a direct current source of energy which supplies either a portion or all of the energy required when such signals are displaying one or the other of the more restrictive indications and which source 25 of direct current energy serves also as a reserve source of current in event of failure of the source of alternating current.

It will be apparent that since the stretch of railway track ordinarily will be unoccupied for 30 the greater portion of the time, the consumption of direct current energy will be relatively small. This feature provides for a material reduction in the cost of maintenance particularly when the direct current energy is supplied by primary 35 batteries.

From the foregoing description, it is apparent that each of the modifications embodying my invention provides a distinctive control for each of three sections in the rear of an occupied section 40 whereby a three block, four indication system of signaling is produced which systems each require but two line control wires extending from signal to signal.

Although I have herein shown and described 45 only four forms of apparatus embodying my invention, it is understood that various changes and modifications may be made therein within the scope of the appended claims without departing from the spirit and scope of my invention. 50

Having thus described my invention, what I claim is:

1. In combination, a plurality of successive sections of railway track each having a track circuit including a track relay, a line circuit for each section governed by the associated track relay, a polarized direct current relay and an alternating current relay for each section connected to the associated line circuit, a source of direct current for each section, an alternator for each section for converting direct current to alternating current, means including back contacts of both said direct current and said alternating current relay for connecting the associated alternator to the associated direct current source and to the line circuit next in rear of the associated section, means including front contacts of the alternating current relay and back contacts of the direct current relay for supplying such rear line circuit with direct current only of reverse polarity, means including front contacts of said direct current relay for supplying such rear line circuit with direct current only of normal polarity and a signal for each section governed by said two associated relays. 75

2. A railway signal system comprising a first and a second as well as a third track section over which traffic normally progresses in the order named, a track circuit including a track relay 5 for each section, a line circuit for each section governed by the associated track relay and including a pair of line wires, a polarized direct current line relay for each section connected to the associated line circuit, an auxiliary line relay 10 for each section also receiving energy from the associated line circuit and responsive only when said line circuit is supplied with alternating current, means including back contacts of both line relays for the third section for supplying alternating current to the line circuit for the second section when the third section is occupied, means including front contacts of the auxiliary relay for the second section and back contacts 15 of the polarized relay for that section for supplying the line circuit for the first section with direct current of reverse polarity, a signal for said first section, and means including reverse polar contacts of the polarized relay for the first section for causing said signal to indicate that the 20 third section is occupied.

3. In combination, a stretch of railway track divided into a plurality of successive block sections each having a pair of conductors governed by traffic conditions in said section, each of said 30 block sections having a signal capable of displaying a normal proceed indication and a plurality of restrictive proceed indications, each of said signals having associated therewith first and second control devices energized from the conductors 35 for the section with which the signal is associated, the first control device being responsive to alternating current supplied to said conductors, the second control device being responsive to direct current supplied to said conductors, each signal 40 having associated therewith an alternating current supply mechanism operative on the supply of direct current thereto to supply alternating current to a circuit from which alternating current may be supplied to the conductors of the 45 adjacent block section to the rear, each signal also having associated therewith a source of direct current, said first control device being operative when energized to condition the signal with which it is associated to display a restrictive 50 proceed indication, the second control device being operative when energized while the first control device is deenergized to condition said signal to display its normal proceed indication, the second device controlling the supply of direct current 55 to the associated alternating current supply mechanism.

4. In combination, a stretch of railway track divided into a plurality of successive block sections each having a pair of conductors governed 60 by traffic conditions in said section, each of said block sections having a signal capable of displaying a normal proceed indication and a plurality of restrictive proceed indications, each of said signals having associated therewith first and second control devices energized from the conductors 65 for the section with which the signal is associated, the first control device being responsive to alternating current supplied to said conductors, the second control device being responsive to direct current supplied to said conductors, each signal having associated therewith an alternating current supply mechanism operative on the supply of direct current thereto to supply alternating current to a circuit from which alternating 70 current may be supplied to the conductors of the adjacent block section to the rear, each signal also having associated therewith a source of direct current, said first control device being operative when energized to condition the signal with which it is associated to display a restrictive proceed indication, the second control device being operative when energized while the first con- 75

the adjacent block section to the rear, each signal also having associated therewith a source of direct current, said first control device being operative when energized to condition the signal with which it is associated to display a restrictive 5 proceed indication, the second control device being operative when energized while the first control device is deenergized to condition said signal to display its normal proceed indication, the first and second control devices jointly controlling the 10 supply of direct current to the associated alternating current supply mechanism, one of said control devices controlling the connection of the source of direct current to the conductors of the adjacent block section to the rear. 15

5. In combination, a stretch of railway track divided into a plurality of successive block sections each having a pair of conductors governed by traffic conditions in said section, each of said block sections having a signal capable of displaying a normal proceed indication and a plurality of restrictive proceed indications, each of said signals having associated therewith first and second control devices energized from the conductors for the section with which the signal is associated, 20 the first control device being responsive to alternating current supplied to said conductors, the second control device being responsive to direct current supplied to said conductors, each signal having associated therewith an alternating current supply mechanism operative on the supply of direct current thereto to supply alternating current to a circuit from which alternating current may be supplied to the conductors of the adjacent block section to the rear, each signal 25 also having associated therewith a source of direct current, said first control device being operative when energized to condition the signal with which it is associated to display a restrictive proceed indication, the second control device being 30 operative when energized while the first control device is deenergized to condition said signal to display its normal proceed indication, said first and second control devices jointly controlling the supply of direct current to the associated alternating current supply mechanism, said first control device also controlling the connection of the source of direct current to the conductors of the adjacent block section to the rear. 35

6. In combination, a stretch of railway track divided into a plurality of successive block sections each having a pair of conductors governed by traffic conditions in said section, each of said block sections having a signal capable of displaying a normal proceed indication and a plurality of restrictive proceed indications, each of said signals having associated therewith first and second control devices energized from the conductors for the section with which the signal is associated, the first control device being responsive to alternating current supplied to said conductors, the second control device being responsive to direct current supplied to said conductors, each signal having associated therewith an alternating current supply mechanism operative on the supply of direct current thereto to supply alternating current to a circuit from which alternating current may be supplied to the conductors of the adjacent block section to the rear, each signal also having associated therewith a source of direct current, said first control device being operative when energized to condition the signal with which it is associated to display a restrictive proceed indication, the second control device being operative when energized while the first con- 65

trol device is deenergized to condition said signal to display its normal proceed indication, said first and second control devices jointly controlling the supply of direct current to the associated alternating current supply mechanism and the connection of the source of direct current to the conductors of the adjacent block section to the rear.

7. In combination, a stretch of railway track divided into a plurality of successive block sections each having a pair of conductors governed by traffic conditions in said section, each of said block sections having a signal capable of displaying a normal proceed indication and a plurality of restrictive proceed indications, each of said signals having associated therewith first and second control devices energized from the conductors for the section with which the signal is associated, the first control device being responsive to alternating current supplied to said conductors, the second control device being responsive to direct current supplied to said conductors, each signal having associated therewith an alternating current supply mechanism operative on the supply of direct current thereto to supply alternating current to a circuit from which alternating current may be supplied to the conductors of the adjacent block section to the rear, each signal also having associated therewith a source of direct current, said first control device being operative when energized to condition the signal with which it is associated to display a restrictive proceed indication, the second control device being operative when energized while the first control device is deenergized to condition said signal to display its normal proceed indication, said second control device controlling the supply of direct current to the associated alternating current supply mechanism, said first and second control devices jointly controlling the connection of the source of direct current to the conductors of the adjacent block section to the rear.

8. In combination, a stretch of railway track divided into a plurality of block sections each having a pair of conductors governed by traffic conditions in said section, each of said block sections having a signal capable of displaying a normal proceed indication and a plurality of restrictive proceed indications, each of said signals having associated therewith a first and a second control device energized from the conductors for the block section with which the said signal is associated, the first control device being responsive to alternating current supplied to said conductors, the second control device being responsive to direct current supplied to said conductors, said second control device being selectively responsive to the polarity of direct current supplied thereto, each of said signals having associated therewith an alternating current supply mechanism operative on the supply of direct current thereto to supply alternating current to a circuit from which alternating current may be supplied to the conductors of the adjacent block section in the rear, each of said signals also having associated therewith a source of direct current, the first control device being operative when energized to condition the signal to display a restrictive proceed indication, the second control device being operative when energized with direct current of a particular polarity at a time when the first control device is deenergized to condition the signal to display the normal proceed indication, the second control device controlling the supply of direct current to the associated alter-

nating current supply mechanism, said first control device controlling the connection of the source of direct current to the conductors of the adjacent block section to the rear.

9. In combination, a stretch of railway track divided into a plurality of block sections each having a pair of conductors governed by traffic conditions in said section, each of said block sections having a signal capable of displaying a normal proceed indication and a plurality of restrictive proceed indications, each of said signals having associated therewith a first and a second control device energized from the conductors for the block section with which the said signal is associated, the first control device being responsive to alternating current supplied to said conductors, the second control device being responsive to direct current supplied to said conductors, said second control device being selectively responsive to the polarity of direct current supplied thereto, each of said signals having associated therewith an alternating current supply mechanism operative on the supply of direct current thereto to supply alternating current to a circuit from which alternating current may be supplied to the conductors of the adjacent block section in the rear, each of said signals also having associated therewith a source of direct current, the first control device being operative when energized to condition the signal to display a restrictive proceed indication, the second control device being operative when energized with direct current of a particular polarity at a time when the first control device is deenergized to condition the signal to display the normal proceed indication, said first and second control devices jointly controlling the supply of direct current to the associated alternating current supply mechanism, said first control device controlling the connection of the source of direct current to the conductors of the adjacent block section to the rear. 40

10. In combination, a stretch of railway track divided into a plurality of block sections each having a pair of conductors governed by traffic conditions in said section, each of said block sections having a signal capable of displaying a normal proceed indication and a plurality of restrictive proceed indications, each of said signals having associated therewith a first and a second control device energized from the conductors for the block section with which the said signal is associated, the first control device being responsive to alternating current supplied to said conductors, the second control device being responsive to direct current supplied to said conductors, said second control device being selectively responsive to the polarity of direct current supplied thereto, each of said signals having associated therewith an alternating current supply mechanism operative on the supply of direct current thereto to supply alternating current to a circuit from which alternating current may be supplied to the conductors of the adjacent block section in the rear, each of said signals also having associated therewith a source of direct current, the first control device being operative when energized to condition the signal to display a restrictive proceed indication, the second control device being operative when energized with direct current of a particular polarity at a time when the first control device is deenergized to condition the signal to display the normal proceed indication, said first and second control devices jointly controlling the supply of direct current to the associated alternating current supply mechanism, said second control de- 75

of direct current to said mechanism, said first control device controlling the connection of the source of direct current to the conductors of the adjacent block section to the rear.

- 5 15. In combination, a stretch of railway track divided into a plurality of block sections each having a pair of conductors governed by traffic conditions in said section, each of said block sections having a signal capable of displaying a
- 10 normal proceed indication and a plurality of restrictive proceed indications, each of said signals having associated therewith a first and a second control device energized from the conductors for the block section with which the said signal is associated, the first control device being responsive to alternating current supplied to said conductors, the second control device being responsive to direct current supplied to said conductors, said second control device being selectively responsive to the polarity of direct current supplied thereto, each of said signals having associated therewith an alternating current supply mechanism operative on the supply of direct cur-
